ELECTRIC BEDCOVERING CONTROL UNIT

Robert L. Smith, Hartsdale, N. Y., assignor to Bobrich Products Corp., New York, N. Y., a corporation of New Jersey

Application November 10, 1954, Serial No. 33,055

Term of patent 7 years

(Cl. D26—13)

Fig. 3.

Fig. 1.

Fig. 2.

Fig. 4.

Fig. 1 is a front elevational view of an electric bedcovering control unit, showing my new design.

Fig. 2 is a side elevational view thereof.

Fig. 3 is a top plan view thereof.

Fig. 4 is a rear elevational view thereof.

The characteristic features of the design reside in the portions shown in solid lines.

I claim:

The ornamental design for an electric bedcovering control unit, substantially as shown and described.
